UNITED STATES PATENT OFFICE

2,290,693

GASEOUS ELECTRIC DISCHARGE
APPARATUS

Harold W. Lord and Martin A. Edwards, Schenectady, N. Y., assignor to General Electric Company, a corporation of New York

Application November 16, 1939, Serial No. 304,755

8 Claims. (Cl. 176—124)

Our invention relates to gaseous electric discharge devices, such as discharge lamps, and apparatus for operating them from alternating current circuits. It relates particularly to discharge devices which have electrodes that are initially heated to an electron emitting temperature and to apparatus which, when the electrodes have reached that temperature, applies the starting voltage to the device. It is the object of our invention to provide apparatus of this character which will produce rapid and ample initial heating of the electrodes, which will have low losses after the starting and during the normal operation of the device and which will eliminate any reset time.

Our invention will be better understood from the following description taken in connection with the accompanying drawing and its scope will be pointed out in the appended claims.

In the single figure of the drawing which is a circuit diagram illustrating one embodiment of our invention, the gas filled electric discharge device or lamp 1 having the initially heated thermionic electrodes 2 at the ends thereof is shown connected through the ballast reactor 3 and the control switch 4 with the source 5 of alternating current supply such for example as a 60 cycle, 115 volt lighting circuit.

Connected across the device 1 and in series with the electrodes 2 is the thermal switch 6 which, for example, may be a bimetallic switch. Normally this switch is in open circuit position and preferably is enclosed in an evacuated envelope. For heating the switch to cause it to close we employ the resistance heater 7 which may be of any well known form such as a coil of resistance wire. Current is supplied to the heater 7 from the secondary 8 of the transformer 9 which is constructed to have high leakage reactance of non-linear characteristics.

The transformer core as shown has a center leg wound with the primary 10 and two outer legs of which one is wound with the secondary 8. The other leg, indicated at 11, becomes saturated when the voltage applied to the primary reaches a predetermined value such as the value initially impressed upon it by the closing of the switch 4 and before the discharge starts in the device 1. The saturation of the leg 11 has a two-fold effect; it forces flux through the secondary to generate heating current and it reduces the inductive reactance of the primary. The capacitor 12 connected in series with the primary is constructed to resonate with the primary when it has its low reactance value. Since the con-

dition of resonance depends upon the saturation of the transformer and the latter depends upon the voltage the circuit comprising the capacitor and the primary may be termed a voltage sensitive non-linear, resonant circuit. After the discharge starts the arc drop voltage between the electrodes is insufficient to maintain saturation in the leg 11, hence the circuit goes out of resonance and as a result the current flow through the primary of the transformer during the normal operation of the discharge device reduces to a very low value at which value the losses in the transformer and in the heating circuit are negligibly small.

The operation of the apparatus will be readily apparent from the above description. When the apparatus is thrown upon the supply circuit by the closing of the switch 4 the device does not immediately start since the line voltage is insufficient in itself to cause a breakdown between the electrodes thereof. Current does flow through the reactor 3, the two filaments 2, the capacitor 12 and the transformer primary. Since the leg 11 saturates at the voltage thus applied to the transformer the capacitor resonates with the primary. The resulting current flow gives the electrodes a certain amount of heat and simultaneously causes current to be induced in the secondary 8 whereby the switch 6 is rapidly heated by the heater 7 and warped into closed circuit position. The low impedance shunt circuit thus provided causes the electrodes quickly to come to an electron emitting temperature. The closing of the switch 6, however, short circuits the circuit 30 of the transformer primary whereby current in the heating circuit is reduced substantially to zero. Upon cooling, the switch opens thereby producing a voltage impulse across the device which effects the starting thereof and after the device has once started the arc drop voltage across it is insufficient to maintain the transformer leg 11 saturated and a condition of resonance in the circuit. By continuing to cool, the switch returns to an open circuit position which is substantially the same as that which is occupied before the switch 4 was closed, since the circuit, being no longer in resonance and the reactance of the primary being high, now supplies only a small amount of energy to the heater. The switch 6 in this position is reset for a subsequent starting operation, hence with apparatus of this character any reset time is entirely eliminated.

What we claim as new and desire to secure 55 by Letters Patent of the United States is:

1. In combination, a source of alternating current supply, an electric discharge device connected to be supplied therefrom and having electrodes between which a discharge takes place constructed to be initially heated to an electron emitting temperature, a normally open thermal switch connected across the device in series with said electrodes, a heater for said switch and a supply circuit for said heater including a reactive impedance having a non-linear characteristic connected across said device.
2. In combination, a source of alternating current supply, an electric discharge device connected to be supplied therefrom and having electrodes between which a discharge takes place constructed to be initially heated to an electron emitting temperature, a normally open thermal switch connected across the device in series with said electrodes, a resistance heater for said switch and a supply circuit for said heater connected to be responsive to the voltage across said device and including current controlling impedance means having a non-linear characteristic.
3. In combination, a source of alternating current supply, an electric discharge device connected to be supplied therefrom and having electrodes between which a discharge takes place constructed to be initially heated to an electron emitting temperature, a normally open thermal switch connected across the device in series with said electrodes, a heater for said switch and means including a transformer having non-linear characteristics connected across said device for supplying heating current thereto.
4. In combination, a source of alternating current supply, an electric discharge device connected to be supplied therefrom and having electrodes between which a discharge takes place constructed to be initially heated to an electron emitting temperature, a normally open thermal switch connected across the device in series with said electrodes, a resistance heater for said switch, and a high leakage reactance transformer having non-linear characteristics, said transformer having its secondary connected to supply said heater and having its primary connected to be responsive to the voltage across said device.
5. In combination, a source of alternating current supply, an electric discharge device connected to be supplied therefrom and having electrodes between which a discharge takes place constructed to be initially heated to an electron emitting temperature, a normally open thermal switch connected across the device in series with said electrodes, a resistance heater for said switch, and means for supplying heating current to said heater comprising a circuit connected in parallel with said switch adapted to resonate in response to the application of starting voltage thereto.
6. In combination, a source of alternating current supply, an electric discharge device connected to be supplied therefrom and having electrodes between which a discharge takes place constructed to be initially heated to an electron emitting temperature, a normally open thermal switch connected across the device in series with said electrodes, a resistance heater for said switch, and means comprising a non-linear resonant circuit connected to be responsive to the voltage across said device for supplying heating current to said electrodes.
7. In combination, a source of alternating current supply, an electric discharge device connected to be supplied therefrom and having electrodes between which a discharge takes place constructed to be initially heated to an electron emitting temperature, a normally open thermal switch connected across the device in series with said electrodes, a resistance heater for said switch, and means for supplying heating current to said heater comprising a transformer having its secondary connected across said heater and having a leakage path constructed to saturate when the starting voltage of the device is applied to the transformer primary and to desaturate when the arc drop voltage of the device is applied thereto, a capacitor and means connecting the capacitor and the primary in a series circuit across said device, said capacitor being constructed to resonate with said primary in response to the saturation of said leakage path.
8. In combination, an electric discharge device arranged to be supplied from a source of alternating current and having electrodes between which a discharge takes place constructed to be initially heated to an electron emitting temperature, a normally open thermal switch connected across the device in series with said electrodes, a heater for actuating said switch, and means having a non-linear volt-ampere characteristic connected across said switch for energizing said heater.
